3 Claims. (Cl. 167—88)

This invention relates to the dyeing of hair, including human hair, and other keratinous materials.

It is known to use, for dyeing hair or other keratinous material, triphenols such as 1,2,4-trihydroxybenzene and 2,4,5-trihydroxytoluene. Nevertheless, using these products alone and at room temperature, it has heretofore been possible only to obtain relatively light shades. To obtain darker shades these compounds have been mixed with other oxidation dyes already known for hair dyeing, such as phenylene-diamines or aminophenols, or with heavy metal salts such as iron salts or copper salts. J. L. Stoves and H. Burton, Journal of the Society of Dyers and Colourists (1950), vol. 66, pp. 474 to 478, indicate (p. 477) that 2,4,5-trihydroxytoluene is capable of dyeing wool in shades from light reddish-brown to dark brown, depending upon whether the solution is adjusted to an acid or an alkaline pH-value, by operating at 90° C. for 1 hour. A process for dyeing hair is also known, in which use is made of the 1,2,4-trihydroxy compounds of benzene (which may also contain other substituents) in the form of their corresponding 1,2,4-triacyl derivatives; such derivatives are saponified a few moments before their application by boiling them in aqueous alcoholic solution in the presence of an excess of an alkaline reactant, such as sodium carbonate. Hence, these saponified derivatives are applied in alkaline medium; whatever the method of oxidation employed (simple oxidation in the air or addition of an oxidizing agent such as hydrogen peroxide), only fairly light shades are obtained.

Another process is known, in which a trihydroxylated compound such as 2,4,5-trihydroxytoluene is employed in aqueous solution, which may be thickened to the form of a cream and which contains in addition an aliphatic mercaptan; there is added to such solution, at the time of application to the hair, ammonia or a primary, secondary or tertiary amine of the aliphatic or cycloaliphatic series, or a salt of any of these. The shades thus obtained, after exposure to the air for about half an hour and at a temperature of 35–40° C., range from golden blond to black, depending upon the particular conditions of the application, always to be effected in alkaline medium.

It is also known to dye hair by means of aqueous or alcoholic solutions of 1,2,4-trihydroxybenzene or of 2,4,5-trihydroxytoluene, which may advantageously be adjusted to an acid pH for application to the hair, the shade being thereafter developed on the hair itself by the addition of an aliphatic or araliphatic primary amine or again, if the dyeing composition already contains a salt of such an amine, by the addition of an alkaline reactant capable of liberating this base.

The latter processes afford a final shade ranging from light chestnut to medium chestnut in the space of about half an hour at room temperature.

All these processes have disadvantages in varying degrees. Thus, although the use of metallic salts does in fact give stable and sufficiently dark shades, it is unde-

2

sirable because of the subsequent chemical treatments to which the hair may be subjected e.g., permanent waving and bleaching. Similarly, the addition of ammonia or of amines to the triphenols employed does accelerate the development of the shade, but since the solutions of these phenols are not stable in alkaline medium, this results in complications of a practical order. Moreover, the shades obtained by means of these triphenols, developed in the presence of amines added before or after the application to the hair or liberated from their salts immediately before or after the application, are not final at the expiry of the treatment period, which is generally half an hour. On the contrary, they continue to change very slowly, even if the development is accelerated by the application of hydrogen peroxide.

It is an object of this invention to provide a process whereby it is possible to directly obtain natural, stable and final shades by means of these same trihydroxylated compounds in a very simple manner. More particularly it provides for obtaining, in a very short time, a substantially permanent pre-selected coloration which is resistant to shampoos and to permanent waving treatments and which is compatible with any subsequent treatment of the hair.

According to the present invention a process for dyeing hair and other keratinous material comprises subjecting the same to the simultaneous action of at least one triphenol of the following general formula:

30

wherein R represents a hydrogen or halogen atom or an alkyl, alkoxy or hydroxyalkyl group, and of a non-gaseous oxidising reactant, preferably an alkali metal or ammonium iodate, periodate or persulphate, in an aqueous medium adjusted to a pH-value of at most 7, allowing the reaction to proceed for the time necessary for the development of the shade, and thereafter washing, rinsing and drying the hair or other material.

The choice of the triphenol or of the respective proportions of the various triphenols employed in mixture, as also the choice of the oxidising agent and of the impregnation time, depend upon the final shade which it is desired to obtain.

The global triphenol concentration of the solution applied to the hair or other keratinous material may vary within fairly wide limits but is preferably between 0.01 mole and 1 mole of triphenol per litre of dyeing solution.

The pH-value of the solutions may vary between 1 and 7. In the case where the solution employed contains one of the aforesaid oxidising agents, account should be taken, in selecting the working pH, of the nature of this oxidising agent. Thus, if an alkali metal or ammonium iodate or periodate is employed as the oxidising reactant, it is preferable not to reduce the pH below 3 and not to employ strong inorganic acids for obtaining low pH values.

The dyeing process according to the invention may be carried out in various ways.

In one preferred method, an aqueous or aqueous-alcoholic solution of the triphenol or of the mixture of triphenols is prepared, to which the inorganic oxidising agent or agents is or are added at the time of application to the hair or other keratinous product. The pH of the solution may be adjusted to the desired value by the addition of any appropriate reactant. If preferred it is even possible to use the solution as such that is to say, without any other constituent than the triphenols and the oxidising agent, the pH then resulting simply

from the respective proportions of these two constituents. Whatever the pH at which the operation is carried out, the solution is preferably left in contact with the hair or other keratinous material for 5-60 minutes and the hair is then briefly rinsed, shampooed, rinsed again and dried. 5

In this method of carrying out the process, the inorganic oxidizing agent or agents may be introduced into the triphenol solution either in the form of powder or in aqueous solution. 10

In another method, the process is carried out in two stages, by first applying the solution of the triphenol or triphenols, free from any oxidizing agent, and allowing this solution to remain in contact with the hair or with the product to be dyed for 5-60 minutes in order to complete the impregnation, partly drying the hair, if desired after rinsing with water, and then applying an aqueous solution of the selected oxidizing agent and leaving it in contact for the period necessary for the development of the shade, generally from 5-20 minutes, the hair then 20 being rinsed, shampooed, rinsed again and dried.

If the pH of the triphenol solution applied in the first stage is not adapted to the nature of the oxidizing agent employed or to the desired effect, or if the brief rinsing which has followed this first application has caused the pH on the hair to revert to a higher excessive value, said value may be modified by adding to the solution containing the oxidizing agent an appropriate reactant, for example an organic or inorganic acid, an acid hydrogen salt or a buffer. However, as noted above, if the oxidizing agent employed is an iodate or periodate it is preferable not to reduce the pH value below 3 and to avoid the use of strong inorganic acids for obtaining low pH values. 30

Whatever the pH chosen for the development of the shade and whether the process is carried out in two stages or in only one stage, the concentration of the oxidizing agent in the solution containing it may be comprised between fairly wide limits, depending upon the desired shade and upon the own solubility of the oxidizing agents which may be employed. Generally speaking, the quantity of 40 oxidizing agent to be employed corresponds to about 0.5 to 10 g. per 100 cc. of the triphenol solution employed, whether or not this solution itself contains the oxidizing agent. The volumes of triphenol solution and/or of oxidizing agent to be employed are based in each case on the bulk of hair to be treated or on the quantity of other keratinous material to be dyed.

The dyeing process of the invention may be carried out not only by means of aqueous solutions as described above, but also by means of creams, pastes or jellies, the adjustment to the required consistency being effected by any conventional method used in hair dyeing. 50

The following examples will serve to illustrate the invention:

Example I

A solution having the following composition is prepared:

G.	
1,2,4-trihydroxybenzene	3
Acetic acid	2
Water to make 100 cc.	

At the time of application, 1.5 g. of powdered sodium iodate is added and, after rapid dissolution of the latter, live, almost white hair is impregnated with this solution. The pH of the mixture is 4. After contact for 15 minutes, the hair is rinsed, shampooed, rinsed again and dried. A light chestnut shade having a golden tinge is thus obtained. 65

Example II

The following solution is prepared:

G.	
1,2,4-trihydroxybenzene	4
Acetic acid	0.5
Water to make 100 cc.	

The pH of this solution is 4. At the time of application to human hair, 2 g. of potassium periodate are added thereto. The solution is left in contact with the hair for 20 minutes, and the hair is then rinsed, shampooed, rinsed again and dried. The shade obtained is light chestnut and has a very natural appearance. 4

Example III

The following composition is employed:

G.	
1,2,4-trihydroxy-5-methylbenzene	4
Water to make 100 cc.	

At the time of application, 2 g. of potassium periodate are added thereto. Nearly white live hair is impregnated with this composition, which is allowed to act for 15 minutes. The hair is rinsed, shampooed, rinsed again and dried. A bright violet-tinged mahogany shade is obtained.

Example IV

The following solution is prepared:

G.	
1,2,4-trihydroxybenzene	3
Acetic acid	2
Water to make 100 cc.	

Immediately before the application of this solution to human hair, 5 g. of sodium persulphate are added thereto. The pH of this solution is 2.3. Live white hair is impregnated with this solution, which is allowed to act for 15 minutes. In contact with the hair, the pH is then equal to 1.1. The hair is rinsed, shampooed, rinsed again and dried. A warm golden chestnut of very natural appearance is obtained.

The following dyeing composition is prepared:

Example V

G.	
1,2,4-trihydroxybenzene	2.5
"Antaron FC 34" (a commercial amphoteric surface-active compound derived from fatty amide)	5
Water and lactic acid to make 100 cc. at pH 3.	

At the time of application, 4 g. of sodium iodate are added to this composition. The pH does not vary. After 45 contact for 15 minutes with live, nearly white hair, the hair is briefly rinsed, shampooed, rinsed again and dried. The shade obtained is light chestnut having a golden tinge.

Example VI

The procedure of the preceding example is followed, but 5 g. of sodium persulphate are added as oxidizing agent at the time of application. The mixture is allowed to act for 15 minutes. On expiry of this period, the pH in contact with the hair has changed from 3 to 1. A light chestnut verging on red is obtained. 55

Example VII

A solution having the following composition is prepared:

G.	
1,2,4-trihydroxybenzene	3
Sodium tartrate	5
Tartaric acid	5
Water to make 100 cc.	

At the time of application to the hair, 5 g. of sodium persulphate are added. The pH of this solution is 3. After 65 impregnation of live white hair, on which the solution is allowed to act for 30 minutes, the pH in contact with the hair falls to 2. After rinsing, shampooing, further rinsing and drying, the hair is dyed golden-blond.

Whilst the invention is of especial importance in relation to the dyeing of human hair it may also be applied, for example, to keratinous materials in the form of fibers, felts, furs and feathers.

What we claim is:

1. A process for dyeing live human hair at room temperature which comprises applying thereto, a freshly prepared aqueous solution containing a triphenol of the general formula

wherein R is selected from the group consisting of hydrogen, halogen, alkyl, alkoxy and hydroxyalkyl, said solution being adjusted to a pH value of at most 7 and containing an oxidizing agent selected from the group consisting of alkali metal and ammonium iodates, periodates and persulphates.

2. A process for dyeing live human hair at room temperature which comprises applying thereto, a freshly prepared aqueous solution containing a triphenol of the general formula

wherein R is selected from the group consisting of hydrogen, halogen, alkyl, alkoxy and hydroxyalkyl, said solution being adjusted to a pH value of at most 7 and containing an oxidizing agent selected from the group consisting of alkali metal and ammonium iodates, periodates and persulphates, said solution containing 0.01 mole to 1 mole of said triphenol per litre and 0.5 to 10 grams of said oxidizing agent per 100 cc.

3. A process for dyeing live human hair at room temperature which comprises applying thereto, a freshly prepared aqueous solution containing a triphenol of the general formula

- 10 wherein R is selected from the group consisting of hydrogen, halogen, alkyl, alkoxy and hydroxyalkyl, said solution being adjusted to a pH value of at least 3 and at most 7 and containing an oxidizing agent selected from the group consisting of alkali metal and ammonium iodates, periodates and presulphates, said solution containing 0.01 mole to 1 mole of said triphenol per litre and 0.5 to 10 grams of said oxidizing agent per 100 cc.
